UNITED STATES PATENT OFFICE.

DUANE W. ALEXANDER, OF AKRON, OHIO.

AUTOMOBILE HEATER.

Application filed July 9, 1917, Serial No. 179,844. Renewed April 21, 1922. Serial No. 555,915.

To all whom it may concern:

Be it known that I, DUANE W. ALEXANDER, a citizen of the United States, residing at Kent, in the county of Portage and State of Ohio, have invented a certain new and useful Improvement in Automobile Heaters, of which the following is a full, clear, and exact description.

This invention relates to heaters which are especially adapted for use on motor cars, whereby the hot exhaust gas from the motor may be utilized to heat air that will be discharged through a register fitted in the floor of the passenger carrying part of the car.

15 The primary objects of the invention are to provide a highly efficient but inexpensive device of the character specified.

In the drawings, Fig. 1 is a vertical central section of a radiator embodying the invention, the section being in the plane indicated by line A—B on Fig. 3; Fig. 2 is a plan view of the radiator with a portion of the radiator plate broken away; Fig. 3 is a horizontal section in the plane of line 25 C—D on Fig. 1.

The device as shown consists of three pieces, namely, the body A, the gas conduit cover B, and the register plate C.

In the body is the air flue 10 which is substantially U-shaped in vertical section, as shown in Fig. 3 of the drawing. Both of the branches 10^a and 10^b of this air flue are open at their upper ends, and the outer inlet branch 10^a is extended above the inner discharge branch 10^b. The space between said two branches serves as a gas conduit 12; and said air flues are so shaped that this gas conduit follows a substantially spiral course from the inlet 12^a thereto, at 30 the outer edge of the body, to a centrally disposed gas chamber 14, with which the spiral gas conduit is connected so that the gas discharged therefrom will enter said chamber in a substantially tangential direction. The outlet 14^a from this central chamber is through the lower end thereof.

The gas conduit cover plate 15 fits within the outer branch of the air flue, and is secured to the body so as to close the upper 45 and otherwise open, part of the spiral gas conduit. This cover plate is formed on its under side with a boss 15^a through which is a cylindrical hole that serves as a bearing for the fan shaft 16 that is rotatably fitted therein. Fixed to the part of this fan shaft below this cover plate are fan blades 17 which are preferably twisted substantially as shown, and are so arranged that the gas which flows somewhat forcefully through the central gas chamber 14 will engage said blades and cause the shaft to rotate.

Fixed to the part of the shaft above the cover plate are inclined fan blades 18. These are located in an air chamber 20 which lies between the cover plate 15 and the register plate 19 which is secured to the top of the body, particularly to the upwardly projecting parts of the air flue. In this register plate are a large number of holes 19^a which communicate with the outer inlet branch of the air flue; and in this register plate are also a very large number of holes 19^b which establish communication with the air chamber in which is the fan.

In the cover plate 15 are numerous holes 15^a which establish communication between this chamber and the discharge branch 10^b of the air flue.

It will be understood that this device is to be secured in a hole in the floor of the car body so that the register plate will thereafter form a part of that floor. The inlet end of the gas conduit is to be connected with the exhaust pipe leading from the engine, while another part of the exhaust pipe or the muffler is to be connected over the outlet at the lower end of the central chamber. When the engine is in operation the hot exhaust gases will be discharged into the spiral gas conduit, and thereby the walls of said conduit will be heated. These walls likewise serve as walls of the air flue, whereby the air in said air flue will be heated. The exhaust gas as it passes into and through the chamber will by its impingement upon the fan blades 17 rotate the shaft, whereby the suction fan formed by blades 18 in the air chamber will be rotated. The result will be that air will be drawn from the car body into the outer inlet branch 10^a of the air flue, and thence into the inner discharge branch 10^b, and thence into the air chamber 20, and will be heated as it so flows. It will be discharged from the air chamber through the numerous openings 19^b in the register plate.

Having described my invention, I claim:

1. An automobile heater containing a gas conduit adapted to be connected with the exhaust manifold of an engine, air flues which are separated from the gas conduit

- by heat conducting partition walls, a gas chamber into which the gas conduit discharges, and an air chamber into which the air flue discharges, combined with a vertical 5 rotatable shaft which extends into both chambers, blades secured to said shaft within the gas chamber in position to be engaged and moved by the gas current which flows therethrough, suction fan blades secured to said shaft within the air chamber, and a perforated register plate over said air chamber and in communication therewith.
- 10 2. An automobile heater containing air flues which are U-shaped in vertical section, a gas spiral conduit in the U-shaped space between the branches of said air flue, and a centrally disposed gas chamber into which the spiral gas conduit discharges,—said gas chamber having its outlet through its lower 15 end, combined with a plate which serves as the top wall of the gas conduit and central gas chamber, an air chamber above said plate in communication with one branch only of the air flue, and a register plate 20 which forms the top of said air chamber.
- 25 3. An automobile heater containing air flues which are U-shaped in vertical section, a gas conduit in the U-shaped space between the branches of said air flue, and a centrally disposed gas chamber into which the spiral gas conduit discharges,—said gas chamber having its outlet through its lower end, a cover plate which serves as the top wall of the gas conduit and central gas 30 chamber, an air chamber above said plate in communication with one branch only of the air flue, a register plate which forms the top of said air chamber, a vertical shaft rotatably mounted in the said cover plate, 35 driving blades fixed to the part of said shaft within said central gas chamber, and suction fan blades secured to the part of the shaft within the air chamber.
- 40 4. An automobile heater comprising a body portion in which are formed air flues that are substantially U-shaped in vertical section and are arranged so that the space between the branches of the air flue shall 45 follow a spiral path, and thereby form a spiral gas conduit, a centrally disposed gas chamber in communication with said spiral conduit, the outer branch of the air flue being extended above the other parts of said 50 body, a cover plate fixed to the top of said body within the outer branch of the air flue and serving to cover said spiral conduit, and having a large number of holes in communication with the inner branch of the air flue, a register plate fixed to the upper 55 end of that part of the body in which is the long branch of said air flue,—said register plate having numerous perforations which communicate with the long branch of said air flue and numerous other perforations which communicate with the space between itself and the plates which cover the gas conduit, a shaft rotatably mounted in the cover plate and extending through the same, twisted blades fixed to the lower end of said shaft, and inclined blades fixed to the end of said shaft above said cover plate.
- 60 5. An automobile heater comprising a casing closed at the sides and bottom said casing having walls which provide a centrally disposed chamber the bottom of the casing having an opening which communicates with said central chamber, the casing having a spirally arranged passageway communicating with the said central chamber, the casing also having an inlet which communicates with an end of said spiral passageway said casing having parallel air passageways which communicate at one end which passageways are separated by convolutions of the spiral passageway, the casing being provided with an air inlet to a part 65 of said passageways and an outlet from the other part of said passageway both the inlet and the outlet being located at the same end of the casing.
- 70 6. An automobile heater comprising a body portion in which are formed air flues that are substantially U-shaped in vertical section and are arranged so that the space between the branches of the air flue shall 75 follow a spiral path and thereby form a spiral gas conduit, a centrally disposed gas chamber in communication with said spiral conduit, the outer branch of the air flue being extended above the other parts of said 80 body, a cover plate fixed to the top of said body within the outer branch of the air flue and serving to cover said spiral conduit, and having a large number of holes in communication with the inner branch of the air flue, a register plate fixed to the upper 85 end of that part of the body in which is the long branch of said air flue,—said register plate having numerous perforations which communicate with the long branch of said air flue and numerous other perforations which communicate with the space between itself and the plates which cover the gas conduit, a shaft rotatably mounted in the cover plate and extending through the same, twisted blades fixed to the lower end of said shaft, and inclined blades fixed to the end of said shaft above said cover plate.
- 90 7. In testimony whereof, I hereunto affix my 95 signature:

DUANE W. ALEXANDER.
